CLAIM

The ornamental design for an ANSI electric meter assembly, as shown and described.

DESCRIPTION

FIG. 1 is a perspective view of an ANSI electric meter assembly having a meter cover in accordance with an embodiment of the present invention.

FIG. 2 is an exploded assembly view of the ANSI electric meter assembly with the meter cover of FIG. 1.

FIG. 3 is an isolated perspective view of the meter cover of FIG. 1.

FIG. 4 is an isolated front view of the meter cover of FIG. 1.

FIG. 5 is an isolated rear view of the meter cover of FIG. 1.

FIG. 6 is an isolated left side view of the meter cover of FIG. 1.

FIG. 7 is an isolated right side view of the meter cover of FIG. 1.

FIG. 8 is an isolated top view of the meter cover of FIG. 1.

FIG. 9 is an isolated bottom view of the meter cover of FIG. 1; and,

FIG. 10 is a perspective environmental view of the ANSI electric meter assembly of FIG. 1 mounted on a meter box on a wall.

The details shown in broken lines are for illustrative purposes only and form no part of the claimed design. The dash-dot-dash broken lines represent boundaries of unclaimed portions of the claimed design and form no part of the claimed design.
